UNITED STATES PATENT OFFICE.

JOSEPH S. TINDALL, OF CEDAR SPRINGS, MICHIGAN.

MOLD-HANDLING APPARATUS.

Application filed August 14, 1922. Serial No. 581,688.

To all whom it may concern:

Be it known that I, JOSEPH S. TINDALL, a citizen of the United States of America, residing at Cedar Springs, in the county of Kent and State of Michigan, have invented certain new and useful Improvements in Mold-Handling Apparatus; and I do hereby declare the following to be a full, clear, and exact description of the invention, such 10 as will enable others skilled in the art to which it appertains to make and use the same.

This invention relates to a novel and effective apparatus for handling molds, particularly, burial vault molds made from concrete usually. It is a primary object and purpose of the present invention to provide a construction by means of which burial vaults of concrete or like material may be 20 readily made and handled with ease and facility. A further object of the invention is to provide an apparatus of this character wherein the vault, after setting and hardening in the form sufficiently may be moved 25 out of the way to make room for the construction of others, the movement of or transportation of the heavy vault and the form in which it is made being very easily and expeditiously accomplished. A still 30 further object is to make this apparatus economically, yet at the same time, make it strong, serviceable and durable so as to be fully capable of withstanding any service to which it may be put. These and various 35 other objects and purposes not at this time specifically stated, together with novel constructions for attaining the same will appear fully as understanding of the invention is had from the following description, 40 taken in connection with the accompanying drawings, in which—

Fig. 1 is an elevation, with parts broken away and in section, of the apparatus constructed in accordance with my invention.

Fig. 2 is an enlarged transverse vertical section taken on the plane of line 2—2, of Fig. 1.

Fig. 3 is a perspective view showing the apparatus set up with a vault form, ready 50 for the placing of the concrete in the form, and

Fig. 4 is a perspective view showing the apparatus after it has been reversed in position, after the vault has been made, and 55 in the operation of removal of said apparatus from the form.

Like reference characters refer to like parts in the different figures of the drawings.

In the construction of the apparatus, two 60 substantially semi-circular segments are provided, each made up of three thicknesses of lumber, the outer members 1 of which are longer than the inner member 2 whereby 65 at each end of each segment a space or recess is left between the ends of the two outer members 1. These segments on their inner sides at two opposed points are cut away to make notches or recesses 3, preferably, having sides at right angles to each 70 other, one side of each notch normally being horizontal and the other vertical. The segments are spaced apart a distance substantially equal to the length of the vault member to be made and are secured in such 75 position, relatively to each other by two members 4 of lumber seating in the notches 3 against the horizontal sides thereof and permanently attached to the segments in any suitable manner, additional securing 80 and strengthening members 5 being provided under the members 4 and at right angles thereto. In practice, I have made the construction of two-inch plank and the same works very satisfactorily, but it is evident that the construction is not necessarily 85 made in this way and may be widely varied as to materials used. On the members 5, I have pivotally connected levelling legs 6 which when turned down into operative position, as shown in Figs. 1, 2 and 3, keep 90 the apparatus level and hold it against rolling movement on the segments.

Levelled in this manner, the vault form 95 may be applied. I have shown the same as comprising an outer metal box-like member, having a bottom 7 and vertical sides and ends 8, associated with which is an inverted smaller member of like construction with a bottom 9 and vertical sides and ends 10. When inverted and placed within the outer member of the vault form, the sides and ends 10 are spaced from the sides and ends 8 of the outer member and the form is open 100 at its upper side for the reception of cementitious material which may be entered into the space between said sides and ends and over the inverted bottom 9 of the inner or core member of the form, whereby a burial vault 11 of cementitious material may 105 be easily made, it being understood that this is one member only of the vault, two sub-

stantially like members being required to complete the vault. It is to be further understood that the vault form shown is for illustrative purposes only, the specific form and construction thereof being no part of the present invention.

The pouring of the cementitious material into the vault form takes place when the apparatus is assembled as shown in Fig. 3. 10 After the concrete or like cementitious material has set sufficiently, the remainder of the apparatus is applied. This consists of two like segments of substantially semi-circular outline, also made of three thicknesses of material, two outer pieces of lumber 12 and a middle thickness 13, at its ends being extended to provide tongues 14 to enter the recesses between the ends of the outer side pieces 1 of the first described segments. 15 These last segments are likewise formed with recesses 15 in opposed sides, similar in form to the notches 3 first described. These segments are placed above the first segments, tongues 14 passing into the recesses in the 20 ends of said first segments, it being evident that a circular wheel at each end of the form is thus made.

The upper sides of the notches or recesses 15 lie a distance above the vault 11, and in 25 practice, I place two boards or plank 16 lengthwise of the vault, one at each side thereof, with the ends of the plank received in said notches 15. I may also place a cross board 17 over the ends of the boards 16, this 30 not being at all essential except as a space filler. Wedges 18 are then driven between the upper sides of the notches at 15 and the cross boards 17, previous to which, however, the segments have been securely connected 35 together in some manner, as for instance by driving wedging keys 19 through openings 20 made in conjunction with each other in the end portions of the outer sides 1 of the first segments and in the tongues 14, as 40 shown. Additional wedges may be used to secure the vault form against movement with respect to the apparatus, whereupon the entire structure may be rolled on the wheels 45 made in effect by the joining of the segments, to any desired place in the factory and away 50 from the place where the concrete is poured into the form. This gets the apparatus out of the way and leaves space for the making 55 of another vault with like apparatus.

If the cementitious material has hardened 60 and set sufficiently, the apparatus may be removed therefrom. In fact it is ready for removal at once as the concrete must have been sufficiently set in the first instance before it is rolled out of the way and to any desired 65 position in the factory or to a store room. When the apparatus is to be removed, it is moved so that its last described segments are in lower position, as shown in Fig. 4, 70 supporting horses 21 being placed under the

boards 16, and if necessary, wedges are driven between the upper sides of said supports and the boards. The wedges 18 are then driven out, freeing the boards 17 which are removed. Keys 19 are driven out and the upper structure lifted up in any desired manner and carried back to the place where the new vault is to be made. The under segments are free and can be removed at once. Thereafter, it is only necessary to 75 remove the vault form, which in commercial vault form is very easily done, the vault being left on the supports 21 and the entire apparatus, excepting the boards 16, being ready for reuse. 80

This construction is practical and has been used with exceptionally satisfactory results. Ease in handling, capability of ready movement thereof to any place where the completed vault is to be left, ready and quick 85 setting up for working operations and general simplicity and durability of the apparatus combine to make the apparatus one of great value. One feature of the apparatus is that the height at which the work is done 90 is convenient in every respect. It is understood that the construction is capable of considerable variation without in any respect changing the nature of the invention, and I do not consider the specific showing made to 95 be in any sense limiting the invention thereto. The invention is defined in the claims appended hereto and all forms of construction coming within their scope are to be considered as comprehended by the invention. 100

I claim:

1. In a construction of the character described, two semi-circular segments spaced apart, members connecting the segments and holding them in spaced apart relation, said 105 segments and members being adapted to hold a concrete receiving form, two additional semi-circular segments, means for detachably connecting said additional segments, one to each of the first segments to 110 complete the circle and make rollers for traversing a plane surface, substantially as described.

2. In an apparatus of the class described, two members having curved outer edges 115 making substantially a half-circle, horizontal members attached to and connecting said first members thereby making a support on which a form for receiving cementitious material may be placed, two additional members having semicircular outer curved edges, means for detachably connecting said additional members to the first members to complete the same and make rollers for moving the entire construction, and means for 120 releasably securing the form in and between said members to hold the same against movement when said rolling movement occurs.

3. In an apparatus of the class described, 125

two spaced apart segments having curved outer sides in the shape of a half-circle, said members on their inner sides being provided with relatively large notches, two flat members seated at their ends in said notches and permanently secured to the segments, said members being located in the same plane and at opposite sides of the segments, means for holding the segments and connected members in position such that said members are in a horizontal plane, a form for receiving cementitious material being adapted to rest on said members, and two similarly shaped segments and means for detachably connecting the same to the first segments, substantially as and for the purposes described.

4. In an apparatus of the class described, a structure adapted to hold a form for receiving a cementitious composition, said structure having end members formed with semi-circular outer edges, and additional members formed with like outer edges adapted to be detachably connected to the said end members, substantially as and for the purposes described.

5. In a construction of the character described, a structure on which a form for receiving cementitious material is adapted to

be placed, said structure having end members formed with semi-circular outer edges, means for releasably holding said structure in position whereby the form thereon is positioned horizontal and level, and means for detachable connection to said end members to complete the circle and make rolling means for movement of the structure and form thereon over a horizontal surface, substantially as described.

6. In a construction of the character described, a structure on which a form for receiving cementitious material is adapted to be placed, said structure having end members of semi-circular outer outline, each of said members being made of a plurality of thicknesses of material, some of which at their ends terminate short of the ends of other of said thicknesses of material, and additional members having semi-circular outline and likewise made of a plurality of thicknesses of material similarly formed at the ends but in alternate relation so as to break joints therewith, said additional members being adapted to have detachable connection with the first members.

In testimony whereof I affix my signature. 55
JOSEPH S. TINDALL.
